[57] CLAIM

The ornamental design for an airplane fuselage nose section, as shown and described.

DESCRIPTION

FIG. 1 is a right-front perspective view of our new nose section design for an airplane;

FIG. 2 is a side elevational view thereof;

FIG. 3 is a top plan view thereof;

FIG. 4 is a front elevational view thereof;

FIG. 5 is a bottom plan view thereof.

FIG. 6 is a cross-sectional view taken as indicated by the line 6—6 of FIG. 5.

Elements shown in broken lines are for illustrative purposes only and are not part of the design sought to be patented.
